Primary Examiner—Cathron B. Matta

[57] CLAIM

The ornamental design for a cantilevered, adjustable, portable computer desk, as shown and described.

DESCRIPTION

FIG. 1 shows a perspective view of the invention.

FIG. 2 depicts a top view shown at a reduced scale.

FIG. 3 shows a back view at a reduced scale.

FIG. 4 is a view from the bottom at a reduced scale.

FIG. 5 is a left to review at a reduced scale; and,

FIG. 6 is a right view at a reduced scale.

Any broken lines showing environmental structures are for illustrative purposes only and form no part of the claimed design.

The surfaces or portions of the article not shown in the drawing or described in the specification form no part of the claimed design.
